J. M. WILLIAMS, JR

INTAKE MANIFOLD AND FUEL VAPORIZER

Filed Oct. 7, 1922

UNITED STATES PATENT OFFICE.

JOHN M. WILLIAMS, JR., OF DAYTON, OHIO.

INTAKE MANIFOLD AND FUEL VAPORIZER.

Application filed October 7, 1922. Serial No. 593,124.

My invention relates to intake manifolds for internal combustion engines and more particularly to hot-spot manifolds such as that described in Letters Patent #1,394,948, 5 Oct. 25, 1921, or in Letters Patent #1,418,270, June 6, 1922.

It is an object of my invention to improve on such devices by providing more efficient gas particles separating and vaporizing 10 means and to this end my invention consists in the arrangement and combination of parts which will be hereinafter described and claimed and from which further objects will be apparent.

15 In the drawing;—

Fig. 1 is a plan view of one embodiment of my invention, partly in section.

Fig. 2 is a rear elevation thereof.

20 Fig. 3 is a rear sectional elevation taken on the line 3—3 of Fig. 1 and looking in the direction of the arrows, and

Fig. 4 is a view similar to Fig. 1 showing a modified form of the invention.

To an internal combustion engine 10 of 25 any plural number of cylinders (in the present instance, an engine of four cylinders is shown) is attached in any well known manner, a hot-spot manifold, generally designated 12. This manifold consists of four delivery tubes 14 of equal length connected directionally about a vaporizer generally designated 16 in the order of firing of the engine cylinders for a purpose hereinafter described. The tubes 14 are each provided 30 with flanges 18 through which securing means 20 are passed to secure a baffle plate 22 which has a number of involute ridges 24 running from the center thereof and adapted to turn a stream of fluid substantially backward upon itself as well as give it a swirling motion. A fuel supply pipe 26 from the carburetor has flanges 28 through which securing means 30 pass into the walls of an exhaust pipe or an exhaust by-pass 32, 32 40 which is secured to the baffle 22 by means of flanges 34 and stud bolts or screws 36. Between the exhaust pipe 32 and baffle 22 in the annular chamber formed by the exhaust pipe and between the exhaust pipe and the 45 fuel supply pipe 26 is clamped a vaporizer member 38 made of a metal having a high coefficient of conductivity and arranged to form a chamber 40 between the baffle 22 and the supply pipe and forming a communicating passage between the supply pipe and the intake tubes 14. This vaporizer 38 is

lapped back and forth upon itself to form a number of annular recesses in order to catch heavy gas particles and vaporize them. It also increases the heating space. The 60 baffle member 22 has orifices 42 which have walls diverging in the direction of flow of the gaseous fuel.

Fuel as vaporized by the carburetor is supplied through the pipe 26 and upon suction 65 of a cylinder the gas is deflected by the baffle 22 back upon itself and at the same time given a whirling motion by the involute flanges 24. Should there be unvaporized particles of fuel in the gas the centrifugal 70 action of the whirling vapor will tend to throw such particles out against and into the annular recesses in the walls of the vaporizer 38 there to be completely vaporized by the heat from the exhaust which is readily conducted by the metal of which the vaporizer is composed. In order to increase the whirl 75 of the gases and thus the centrifugal force, I have arranged the intake pipes to supply the cylinder charges in rotation, i. e. in accordance with the firing order. The engine shown will have a firing order of 1, 4, 3, 2 and the intake pipes will be arranged as shown in Fig. 2 in accordance therewith, so that they suck successively in the direction 80 of initial rotation of the gases. Each pipe 14 is made of the same length in order to provide a more equal distribution of the fuel.

In Fig. 4 I have shown a modification 85 wherein the gases flowing toward the engine 90 are swirled by impinging upon a baffle 60 and the heavy particles deflected into annular recesses 62 in the vaporizing member 58. The intake pipes 64, 64 may be arranged 95 in the same manner as those shown in Fig. 2 to increase the whirling effect. The exterior surface of the vaporizer 58 may be abutted in intimate contact with a flat on the exhaust manifold for indirect conduction of heat therefrom.

100 What I claim is:

1. In a vaporizing device for use in a fuel supply system of internal combustion engines, means interposed in the fuel passage between the carburetor and intake ports of said engine for vaporizing unvaporized fuel particles comprising, a baffle having involute flanges and placed at right angles to the direction of flow of gaseous particles through the said passageway and 105 adapted to whirl said particles, heater means in said passageway having annular recesses 110

arranged at right angles to the resulting path of said particles from said baffle, and means to heat said heater means.

2. In combination in a fuel supply system for use in internal combustion engines, means interposed between the carburetor and the inlet ports of said engine for vaporizing unvaporized fuel, intake pipes of equal length leading from said vaporizing means to said inlet ports, a fuel supply pipe leading from the carburetor to said vaporizing means, a baffle in said vaporizing means interposed between said intake and supply pipes to direct gaseous fuel at right angles to its incoming path, means integral with said baffle for whirling said fuel, heater means disposed at right angles to the path of flow of fuel from said baffle means and having recesses therein, and means for heating said heater means, said intake pipes being connected to their respective cylinders

in such order as to successively add to the whirling impulse given said fuel.

3. In combination, in an intake manifold for internal combustion engines, a fuel supply pipe leading from a carburetor of said engine into an annular delivery chamber, said delivery chamber having a baffle therein disposed at right angles to the incoming fuel path, involute directional vanes on 25 said baffle, said delivery chamber walls having annular recesses therein and constructed of a material having a high co-efficient of conductivity, means for heating said walls, and cylinder intake pipes leading from said 30 chamber to the intake ports of said engine and disposed transversely to the resulting direction of flow of said fuel from said baffle.

In testimony whereof I affix my signature

JOHN M. WILLIAMS, JR.
